UNITED STATES PATENT OFFICE

HAGE W. HUCKNALL, OF ELYRIA, OHIO, ASSIGNOR TO THE AMERICAN LACE MANUFACTURING COMPANY, OF ELYRIA, OHIO, A CORPORATION OF OHIO

DESIGN FOR A LACE SCARF OR SIMILAR ARTICLE

Application filed October 6, 1932. Serial No. 45,236. Term of patent 3½ years.

To all whom it may concern:

Be it known that I, HAGE W. HUCKNALL, a citizen of the United States, residing at Elyria, in the county of Lorain and State of Ohio, have invented a new, original, and ornamental Design for a Lace Scarf or Similar Article, of which the following is a specification, reference being had to the accompanying drawing, forming a part thereof.

The single figure in the drawing illustrates exactly one-half of the lace scarf showing my new design, it being understood that the other half repeats in opposing relationship.

I claim:

The ornamental design for a lace scarf or similar article, substantially as shown and described.

HAGE W. HUCKNALL.
